United States Patent

Des. 240,338
Patented June 22, 1976

240,338

MULTI-HEAD COMB

Bernard Suchowski, Marlboro, David D. Lovitz, Short Hills, and Claud W. Kissin, Fort Lee, N.J., assignors to The Hartz Mountain Corporation, Harrison, N.J.

Filed Jan. 30, 1975, Ser. No. 545,628

Term of patent 14 years

Int. Cl. D28—03

U.S. Cl. D86—8

FIG. 1 is a front elevational view of a multi-head comb showing our new design, the rear being identical;

FIG. 2 is a side elevational view thereof;

FIG. 3 is an end elevational view thereof;

FIG. 4 is an opposite end elevational view thereof; and

FIG. 5 is a sectional view taken on line 5—5 of FIG. 1.

We claim:

The ornamental design for a multi-head comb, as shown and described.
